United States Patent Office.

ROBERT WRIGHT, OF PHILADELPHIA, PENNSYLVANIA.

Letters Patent No. 72,352, dated December 17, 1867.

IMPROVEMENT IN BRICKS FOR PAVEMENTS, &c.

The Schedule referred to in these Letters Patent and making part of the same.

TO ALL WHOM THIS MAY CONCERN:

Be it known that I, ROBERT WRIGHT, machinist, residing No. 619 Green street, in the city of Philadelphia, and State of Pennsylvania, have invented a new and improved Brick. I do hereby declare the following to be a full and clear description of the same, reference being had to the accompanying drawings A, B, C, D, E, F, G, H, making a part of this specification.

This invention relates to a new and useful improvement, consisting of a combination of materials forming footpath-pavements, floors, carriage-ways, and for other purposes. The combination is designed to increase the durability, and add to the appearance of the same, which is obtained by the employment of metals in a peculiar manner, in combination with clay bricks; these materials either fused, worked, or cast into such forms as may be required in forming the various letters alphabetical, figures decimal, or other designs.

To enable those skilled in the manufacture of bricks to understand my invention, I will proceed to describe it more fully and with reference to the drawings.

First. When pin-letters, figures, or other designs are required, pierce or mould in the bricks recesses or holes of the shapes and depths necessary, and then burn the bricks. This done, prepare the metals to such sizes as will fit the recesses and force them therein. Or, when it is preferred, fuse the metals, and pour into the recesses.

Second. When plate-letters, figures, or other designs are required, first prepare them, then press them into the brick while it is in a plastic state, and afterwards burn them.

Explanation of the Drawings.

A A and B represent the face-edge and end of a brick, A. A has inserted fifteen pieces of round metal wire, as shown at No. 1, and B has two half round head-pins, as shown at No. 2.

C represents the end of a brick with round metal pins, as shown at No. 3, forming figures decimal.

D represents the edge of a brick with round metal pins, as shown at No. 3, and forming letters alphabetical.

E represents the face of a brick with round metal pins, forming a design shown thereon.

F represents the end of a brick with ten square metal pins, as shown at No. 6.

G represents the edge of a brick with five metal pieces, as shown at No. 4.

H represents the face of a brick with six metal letters, each having a proper root by which they are secured in the brick, and as shown at No. 5.

No. 8 represents a finished burnt brick, containing eleven round metal pins pressed into the same after being burnt.

No. 9 represents also a burnt brick which has eleven holes pierced ready to receive the metallic pins.

No. 10 represents also a burnt brick having eleven metal pins pressed therein previous to burning the brick.

In preparing bricks for foot or other paths, I endeavour so to arrange the metallic parts, leaving sufficient space between each piece to prevent slipping of persons walking over them.

Having thus described my invention, what I claim as new and useful, and desire to secure by Letters Patent, is—

A clay brick, having pieces of metal set into it and coming to its surface, substantially as and for the purposes herein set forth.

ROBERT WRIGHT.
